UNITED STATES PATENT OFFICE

2,068,059

MASTER FEED FOR DUPLICATING MACHINES

Alfred Marchev, La Grange, Ill., assignor to Ditto, Incorporated, Chicago, Ill., a corporation of West Virginia

Application April 27, 1936, Serial No. 76,645

8 Claims. (Cl. 101—132)

This invention relates to duplicating machines of the general type shown in the application of Alfred Marchev, Serial No. 67,468, filed March 6, 1936, for margin control for duplicating machines.

5 Machines of this type employ master sheets which are mounted upon a drum, and copy sheets are fed into contact with the master sheet, a suitable solvent being employed to dissolve off a portion of the ink or carbon on the master 10 sheet so that the same will be transferred to the copy sheets brought into contact therewith.

Master sheets have the date to be duplicated formed thereon in reverse so that, when a portion of the ink is dissolved off and transferred 15 to the surface of the copy sheet, it will appear in correct readable form. In practice, some readily volatile solvent such as alcohol is employed.

20 The present invention is embodied in a machine of the type described which machine comprises a rotary drum having means for clamping master sheets thereto.

25 The machine also has suitable means for advancing copy sheets to the drum which means includes a pair of feed rollers. One of the feed rollers cooperates with the moistening device so that this feed roller will supply the volatile solvent to one surface of a copy sheet as it is fed to the drum. A platen roller is employed to 30 press the copy sheets against the master sheets secured on the drum.

35 The present machine embodies certain improvements whereby the changing of the master sheet may be accomplished with greater ease and with a minimum loss of time in the making of copies. It is particularly advantageous where relatively few copies are being made from any master sheet and where it is necessary to change the master sheet quickly.

40 The features and advantages of the invention will more readily appear as the following description progresses, reference being had to the accompanying drawings wherein—

45 Fig. 1 is a plan view of a duplicating machine which embodies the invention;

Fig. 2 is a sectional view on the line 2—2 of Fig. 1;

50 Fig. 3 is a sectional view similar to Fig. 2 showing a changed position of the mechanism, certain parts being broken away to more clearly illustrate the structure;

55 Fig. 4 is a fragmentary sectional view similar to Fig. 2 illustrating another position of the mechanism; and

Fig. 5 is a sectional view through a master sheet tray employed in the machine.

Referring now to the drawings in which a preferred embodiment of the invention is shown, the reference characters 6 and 7 designate a 5 pair of side frames adapted to rest upon any suitable support. The side frames 6 and 7 are secured together by any suitable means such as that shown in the aforementioned application. A drum 8 is rotatably journaled in the side 10 frames 6 and 7 by means of a suitable shaft 9. This drum is adapted to be rotated by means of a hand lever 10 through suitable gearing not shown which gearing is housed in a gear housing 15 on the side frame 7.

The drum 8 has a large gear 12 secured to the end thereof adjacent to the side frame 7. This gear 12 meshes with an intermediate gear 13 that in turn drives a gear 14 for rotating a combined feeding and moistening roller 15. A 20 felt covered roller 16 cooperates with the roller 15 to advance copy sheets to the drum 8, and a platen roller 17 is adapted to press copy sheets against a master sheet on the drum. A moistening receptacle 18 is supported in front of the 25 moistening roller 15 and is adapted to supply a solvent liquid to the surface of the roller 15 through a suitable wick not shown. A copy sheet table 19 is supported on the side frames 6 and 7 and projects beneath the moistening receptacle 30 18 to aid in feeding copy sheets between the rollers 15 and 16.

The drum 8 is provided with a plurality of grippers 20 which are adapted to project through suitable openings 21 provided in the surface of 35 the drum 8 and to clamp one edge of a master sheet 22 in a groove 23 which runs longitudinally of the drum 8. The grippers 20 are mounted upon a gripper shaft 24 which is journaled in the ends of the drum 8. The shaft 24 has a lever 40 arm 25 fixed thereto exteriorly of the drum at one end thereof. This lever 25 has its free end 26 provided with a pin 27 to which a spring 28 is secured, the other end of the spring 28 being secured to a pin 29 on the end of the drum. 45

The lever 25 has a curved cam surface 30 which may be projected beyond the periphery of the drum in certain instances for a purpose which will be more fully described hereinafter.

The spring 28 normally holds the lever 25 in 50 the position shown in Fig. 2 which is the position for holding the grippers 20 in closed position upon the master sheet 22. The lever 25 carries a roller 31 which is adapted to be engaged with a plurality of cam levers 32 and 33 that are piv- 55

oted upon stub shafts 34 and 35 mounted on the adjacent side frame 7. Coil springs 36 and 37 are secured to the levers 32 and 33, respectively, to normally hold these levers in position shown in Fig. 2. A hand lever 38 has a hub 39 pivoted on the shaft 8. The hub 39 carries a pair of rollers 40 and 41 which are adapted to engage the cam levers 32 and 33 for moving these levers outwardly into position to force the roller 31 and with it the lever 25 outwardly to effect an opening of the grippers 20.

Referring now to Fig. 3 and Fig. 2, it will be noted that shifting of the hand lever 38 from the position shown in Fig. 2 to the position shown in Fig. 3 causes the roller 40 to move the cam lever 32 outwardly into the path of the roller 31 on the lever 25 so as to swing this lever outwardly to open the grippers 20 and release the master sheet 22. The roller 41 in this position has also forced out the cam lever 33 so that, when the drum rotates around to bring the roller 31 over the cam lever 33, the grippers will also be opened. This latter position of the drum 8 and the lever 25 is shown in Fig. 4.

The master sheet 22 is carried upon a tray 42 which is pivotally mounted upon studs 43 by means of depending side portions 44 and 45 formed on the tray 42. The tray 42 is urged toward the drum 8 by means of a spring 46 secured to a pin 47 on the side portion 44, the other end of the spring 46 being secured to a collar 48 that is formed on a stud 49 projecting from the side frame 47. The depending portion 44 of the tray 42 has a projection 50 which extends into engagement with a pin 51 mounted upon a block 52 which is pivoted upon a stub shaft 53 mounted in the side frame 7. The block 52 carries an adjustable stop member 54 which is adapted to engage a tie rod 55 that connects the side frames 6 and 7 to limit the movement of the block 52 in a clockwise direction. A spring 56 (see Fig. 3), secured to a pin 57 on the block 52 and secured at its other end to the side frame 7 by means of a pin 58, is adapted to urge the block 52 in a clockwise direction so as to move the pin 51 away from the projection 50. The block 52 carries an arm 59 which has a pin 60 that is slidable in a slot 61 of a link 62, the link 62 being pivoted at 63 to a projection 64 on the hub 39 of the hand lever 38.

When the hand lever 38 is in the position shown in Fig. 2, the link 62 pulls the block 52 in a counterclockwise direction so that the pin 51 engages the projection 50 and holds the master tray 42 away from the drum 8. However, when the lever 38 is moved into the position shown in Fig. 3, this permits the block 52 to turn in a clockwise direction so as to withdraw the pin 51 from the projection 50. The spring 46 then pulls the master tray 42 down toward the drum 8.

The master tray carries a stop member 65 which engages the surface of the drum at one end thereof and limits the movement of the tray 42 toward the drum 8. The master tray also carries a stop finger 66 which projects across the front end of the tray to hold the master sheet 22 away from the drum upon the tray 42. The stop finger 66 is secured to the shaft 67 pivotally supported by the side portions of the tray 42, and this shaft 67 has a lever arm 68 thereon which extends down along side the end of the drum 8 and carries a roller 69 which is positioned to engage the cam surface 30 of the lever 25. Normally the cam surface 30 is held in by the spring 28 so that it does not engage the roller

69 when copies are being made. However, when the lever 38 is moved to the position shown in Figs. 3 and 4, this causes the lever 25 to be moved out so that its cam surface 30 engages the roller 69 so as to move the arm 68 in a counterclockwise direction and withdraw the stop finger 66 from beneath the master sheet 22.

The stop member 65, while riding upon the surface of the drum 8, prevents this action from taking place by holding the tray 42 away from the drum. However, when the grippers 20 approach master sheet receiving position, the stop member 65 drops into a recess 70 provided in the surface of the drum 8, and this permits the roller 69 to drop down against the surface 30 so as to withdraw the stop finger 66. The master sheet 22 can then slide down into the open grippers 20 by its own weight after which the operation may close the grippers by moving the arm 38 back to the position shown in Fig. 2 which will cause the tray 42 to be lifted back to its resting position and will permit the lever 25 to be drawn inwardly by the spring 28.

The stop finger 66 operates through an opening 71 in a spring clamp plate 72 secured to the forward edge of the tray 42. The shaft 67 has a squared portion 73 between the side portions 44 and 45 of the tray 42 to which the stop fingers 66 are fixed. The stop fingers 66 are held in raised position by means of a torsion spring 74 which is wound on the shaft 67 and anchored at one end to the lever arm 68 and at the other end to the side 44 of the tray 42.

The operation of the device, it is believed, will be clear from the description hereinbefore given. The principal advantage lies in the fact that a master sheet 22 may be placed upon the tray 42 at any time by the operator, and it will not be released until such time as the grippers 20 are opened and brought into alignment with the master tray 42. This permits the operator to place fresh master sheets on the tray 42 while he is making copies from a master sheet already applied to the drum 8.

While certain embodiments of the invention have been shown and described, it is to be understood that it is capable of many modifications. Changes, therefore, in the construction and arrangement may be made without departing from the spirit and scope of the invention as disclosed in the appended claims in which it is the intention to claim all novelty inherent in the invention as broadly as possible in view of the prior art.

Having thus described the invention, what I claim as new and desire to secure by Letters Patent is:

1. In a duplicating machine of the character described, a frame, a drum rotatably journaled therein, said drum having a means thereon to clamp a master sheet thereto, copy sheet feeding rolls adjacent to the drum, means interconnecting the drum and said rollers whereby to cause rotation of the rollers when the drum is rotated, a hand lever, means operable by said hand lever to open said clamping means, a master sheet tray having means thereon to hold a master sheet in position to be fed into the open clamping means and mechanism operable by the clamp opening means to release the master sheet held on said tray when the clamping means is aligned with the master sheet tray in open position.

2. In a duplicating machine of the character described, a frame, a drum pivotally mounted therein, master sheet clamping means on said drum, a master sheet tray having one edge adja-

cent said drum, a stop member movably mounted adjacent to said edge, and adapted in one position to hold a master sheet on said tray away from the drum, said stop member being movable out of said holding position to permit a master sheet on said tray to advance to the drum, control means to open and close said clamping means, and means operable upon alignment of said clamping means with the adjacent edge of the tray to move the stop member out of holding position when the clamping means is open.

5. In a duplicating machine of the character described, a frame, a drum rotatably journaled therein, master sheet clamping means on said drum, a master sheet tray having one edge adjacent said drum, stop means movably mounted on said tray to hold a master sheet thereon away from the drum, and mechanism to withdraw said stop means operable only when the clamping 10 means is in open position and in position to receive a master sheet from said tray.

6. In a duplicating machine of the character described, a frame, a drum rotatably journaled therein, master sheet clamping means on said drum, a master sheet tray having one edge adjacent said drum, stop means movably mounted on said tray to hold a master sheet thereon away from the drum, and mechanism to withdraw said stop means operable only when the clamping 20 means is in open position and in position to receive a master sheet from said tray, said stop means comprising a stop finger extending across the front edge of said tray and pivoted to said tray.

7. In a duplicating machine of the character described, a frame, a drum rotatably journaled therein, master sheet clamping means on said drum, a master sheet tray having one edge adjacent said drum, stop means movably mounted on said tray to hold a master sheet thereon away from the drum, and mechanism to withdraw said stop means operable only when the clamping 30 means is in open position and in position to receive a master sheet from said tray, said stop means comprising a cam movably mounted on the drum and movable outwardly upon opening of said clamping means, and a cam engaging lever arm secured to said stop means.

8. In a duplicating machine of the character described, a frame, a drum rotatably journaled therein, master sheet clamping means on said

therein, master sheet clamping means on said drum, a master sheet tray having one edge adjacent said drum, stop means movably mounted on said tray to hold a master sheet thereon away from the drum, and mechanism to withdraw said stop means operable only when the clamping means is in open position and in position to receive a master sheet from said tray, said mechanism comprising a cam movably mounted on the drum and movable outwardly upon opening of 10 said clamping means, and a cam engaging lever arm secured to said stop means, said drum and tray having cooperating parts to hold said lever arm away from said cam when the clamping means is not in position to receive a master sheet 15 from said tray.

7. In a duplicating machine of the character described, a frame, a drum rotatably journaled therein, master sheet clamping means on said drum, a master sheet tray having one edge adjacent said drum, stop means movably mounted on said tray to hold a master sheet thereon away from the drum, and mechanism to withdraw said stop means operable only when the clamping 20 means is in open position and in position to receive a master sheet from said tray, said stop means comprising a stop finger extending across the front edge of said tray and pivoted to said tray, said mechanism comprising a cam movably mounted on the drum and movable outwardly 25 upon opening of said clamping means, and a cam engaging lever arm secured to said stop means.

8. In a duplicating machine of the character described, a frame, a drum rotatably journaled therein, master sheet clamping means on said drum, a master sheet tray having one edge adjacent said drum, stop means movably mounted on said tray to hold a master sheet thereon away from the drum, and mechanism to withdraw said stop means operable only when the clamping 30 means is in open position and in position to receive a master sheet from said tray, said stop means comprising a stop finger extending across the front edge of said tray and pivoted to said tray, said drum and tray having cooperating parts to 40 prevent actuation of said mechanism when the clamping means is not in position to receive a master sheet from said tray.

ALFRED MARCHEV.
